US00D803299S

(12) **United States Design Patent** (10) **Patent No.:** **US D803,299 S**
(45) **Date of Patent:** **** Nov. 21, 2017**

(54) **EYEWEAR**

(71) Applicant: **Modne, Inc.**, Cerritos, CA (US)

(72) Inventors: **Saehee Park**, Arcadia, CA (US); **Judy Chung**, Arcadia, CA (US); **Kidong Kwon**, Glendale, CA (US); **TaeHun Kim**, Irvine, CA (US)

(73) Assignee: **Modne, Inc.**, Cerritos, CA (US)

(**) Term: **15 Years**

(21) Appl. No.: **29/563,275**

(22) Filed: **May 3, 2016**

(30) **Foreign Application Priority Data**

Nov. 26, 2015 (KR) 30-2015-0059742

(51) **LOC (10) Cl.** **16-06**

(52) **U.S. Cl.**

USPC **D16/326**; D16/327

(57) **CLAIM**

The ornamental design for the eyewear, as shown and described.

DESCRIPTION

FIG. 1 is an isometric view of the front of eyewear;

FIG. 2 is a front view of the eyewear;

FIG. 3 is a back view of the eyewear;

FIG. 4 is a right side view of the eyewear;

FIG. 5 is a left side view of the eyewear;

FIG. 6 is a top view of the eyewear; and,

FIG. 7 is a bottom view of the eyewear.

The broken lines in the drawings represent portions of the
eyewear that form no part of the claimed design.

1 Claim, 5 Drawing Sheets
